UNITED STATES PATENT OFFICE.

EDWIN F. HULBERT, OF MILWAUKEE, WISCONSIN, ASSIGNOR TO JIFFY DESSERT COMPANY, OF WAUKESHA, WISCONSIN, A CORPORATION OF WISCONSIN.

METHOD OF FORMING CLOSURES OF SEALED RECEPTACLES.

1,385,830.

Specification of Letters Patent.

Patented July 26, 1921.

Application filed October 4, 1919. Serial No. 328,576.

To all whom it may concern:

Be it known that I, EDWIN F. HULBERT, a citizen of the United States, residing at Milwaukee, in the county of Milwaukee and 5 State of Wisconsin, have invented certain new and useful Improvements in Methods of Forming Closures of Sealed Receptacles, of which the following is a specification, reference being had therein to the accompanying drawings, forming a part thereof.

My present invention relates to the method of forming a more perfect closure on sealed receptacles by a simple process without the necessity of use of paste, 15 adhesion of wax, metallic fastening means, or tongues, slots or other devices punched from the paper.

My seal is capable of use on bags of the general form shown in the patent to O. E. 20 Glidden and A. S. Nico, No. 1,101,430 of November 15, 1912, or that to A. S. Nico, in Patent No. 1,310,288 of July 15, 1919, and avoids the difficulties in closing encountered thereby in that the completed seal at 25 the mouth of the receptacle is formed by lapping the paper at a sharp angle and keeping it intact so that it is integrally sealed, and indentations or tongues are avoided as they never hold tightly, and give 30 means whereby the receptacle if loaded with powdery material can work up through the folds and out through the indentations or slots. I am also enabled by my present method and means to make a bag and closure 35 sure in two simple operations as against the three or more steps that are necessary as now used.

I have found by experience that the methods of sealing and closing paper bags heretofore in use are defective in that they attempt to make indentations, corrugations, etc. throughout the entire length of the closure, thus tearing and weakening the paper and affording openings through 45 which the contents may escape. The elastic limit of paper is small and I therefore employ corrugations of so small an extent as not to exceed the elastic limit of the paper.

In the figures, Figure 1 shows a side view 50 with the mechanism I employ to create the closure after the bag has had the mouth thereof inserted therein. Fig. 2 shows the mechanism making the primary closure of the bag. Fig. 3 shows it ready for the final

closure, and Fig. 4 shows the corrugations 55 which may be added thereto if desired.

In the drawings 1 indicates the bag, 2 the lapped material at the mouth thereof, 3 a jaw having a notch 4 in the lower portion thereof, 5 a further jaw having a hinged 60 angle piece 6 thereon provided with a toe 7. The angle piece 6 is hinged to the jaw 5 by a pin 8 and has a motion limiting stop 9 so as to prohibit the toe 7 from falling below a predetermined point. The toe 7 65 is kept in that position by a spring 10. The jaws 3 and 5 are movable relatively to each other and when the mouth 2 of the bag 1 is inserted, the jaws 3 and 5 are then brought together until they occupy the position found 70 in Fig. 2, the jaw 3 moving into the relative position shown by the dotted lines in Fig. 1. The motion is then continued until the rounding end of the jaw 3 strikes the face of the angle plate 6 causing the toe 75 thereof 7 to rise vertically, thus forcing the mouth 2 of the bag 1 into intimate and firm contact with the notch 4. When the jaws 3 and 5 separate the toe 7 drops immediately, leaving the mouth 2 of the bag 1 80 formed into a sharply acute angle and effecting a seal thereby.

The seal is completed by having two jaws 12, preferably, with partially corrugated bases, that approach one another and pinch 85 the free ends of the lapped material of the bag 2 into intimate contact, giving a final closure as shown at 13 in Fig. 4. Owing to the small elastic limit of paper as generally used for this class of work, I find that 90 a partial corrugating of the mouth is preferable as not rupturing the paper, thus avoiding weakening the closure and defeating the whole object. All of this is accomplished with but two sets of jaws. 95

Having thus completely described my invention, I claim:

1. The method of closing a sealed receptacle composed of a single sheet of material, which consists in folding the free margins of the mouth thereof upon themselves so as to form a sharply acute angle, pressing the same hard so that they will retain their position and corrugating portions of the free marginal ends and the upper portion of the bag adjoining the mouth thereof into intimate contact. 100

2. The method of closing a sealed recep-

5. A machine for closing sealed receptacles composed of a single sheet of material, which consists in folding the free margins of the mouth thereof upon themselves so as to form a sharply acute angle, pressing the same hard so that they will retain their 10 position and corrugating only so much of the free marginal ends and of the upper portion of the bag adjoining the mouth thereof as will not transcend the elastic limit 15 of the material into intimate contact.

3. A machine for closing sealed receptacles which consists of a primary pair of jaws having a lateral motion relative to each other, one of these jaws being formed 15 with an upwardly projecting nose and notch on one side thereof and the other of said jaws being formed with movable means adapted to coact with said nose and notch.

4. A machine for closing sealed receptacles which consists of a primary pair of jaws having a lateral motion relative to each other, one of these jaws being formed with an upwardly projecting nose and a notch on one side thereof and the other of said 25 jaws being formed with movable means adapted to coact with said nose and notch, and a secondary pair of jaws having a motion relative to each other and adapted to complete the closure by pressing the free 30 marginal ends of the bag into intimate contact.

5. A machine for closing sealed recepta-

cles which consists of a primary pair of jaws having a lateral motion relative to each other, one of these jaws being formed with 35 an upwardly projecting nose and a notch on one side thereof and the other of said jaws being formed with movable means adapted to coact with said nose and notch, and a secondary pair of jaws having motion relative to each other and adapted to 40 complete the closure by pressing the free marginal ends of the bag into intimate contact, and corrugating portions thereof.

6. A machine for closing sealed receptacles which consists of a primary pair of jaws having a lateral motion relative to each other, one of these jaws being formed with an upwardly projecting nose and notch on one side thereof, the other of said jaws having pivoted bell crank shaped means adapted 45 to contact with said nose and being provided with a toe thereon which on the said contact will coact with said notch, a motion limiting stop preventing the motion of said bell crank means beyond a predetermined 50 point in the opposite direction, and a spring for holding said bell crank means in engagement with said motion limiting stop when not in the operative position.
